UNITED STATES PATENT OFFICE.

GEORGE ADOLPH STEINER, OF SALT LAKE CITY, UTAH, ASSIGNOR TO STEINER SALES COMPANY, OF SALT LAKE CITY, UTAH, A CORPORATION OF UTAH.

TOWEL CABINET.

Application filed January 7, 1922. Serial No. 527,749.

To all whom it may concern:

Be it known that I, GEORGE A. STEINER, a citizen of the United States, resident of Salt Lake City, county of Salt Lake, State of Utah, have invented certain new and useful Improvements in Towel Cabinets, of which the following is a specification.

The object of my invention is to provide a towel cabinet of the type where the clean 10 towel is dispensed or delivered from the roll and the soiled portion simultaneously wound upon another roll.

A further object is to provide improved means for guiding and preventing the soiled 15 portion of the towel from twisting during its passage to the soiled towel roll and also preventing any unauthorized person from having access to the clean towel roll.

Other objects of the invention will appear 20 from the following detailed description.

The invention consists generally in various constructions and combinations, all as hereinafter described and particularly pointed out in the claims.

25 In the accompanying drawings forming part of this specification,

Figure 1 is a vertical sectional view through a towel cabinet embodying my invention, on line 1—1 of Fig. 2,

30 Figure 2 is a sectional view on the line 2—2 of Figure 1.

Figure 3 is a detail view of the feed roll chain drive.

In the drawing, 2 represents a cabinet 35 having a front door 3 which, when opened, allows access to the towel roll within. The side walls of the cabinet have guideways 4 and 5 for the clean and soiled towel rolls 6 and 7 mounted on shafts 8 and 9, the ends of 40 said shafts being adapted to slide in the guideways 4 and 5 and rest by gravity upon the feed or control rolls 10 and 11 mounted on shafts 12 and 13 and having a driving sprocket chain 14 between them so that 45 when one feed roll is revolved, a simultaneous movement will be imparted also to the other roll.

I prefer to mount the clean towel roll in the lower guideways 4 and allow the clean 50 portion of the towel to depend therefrom through the bottom of the cabinet and to prevent anyone from reaching up under the clean towel roll or having access thereto through the bottom of the cabinet, I prefer 55 to mount a bracket 15 on the door 3 which,

when the door is closed, will assume the position shown in Figure 1 and compel the user of the towel to pull downwardly in a direct line thereon and exert a considerable downward pressure on the clean towel roll and 60 the roll 10. The soiled portion of the towel, after use, is carried up in the rear of the cabinet to the soiled towel roll to be wound thereon simultaneously with the unwinding 65 of the clean towel.

I prefer to provide a shield in the rear of the cabinet consisting of side rails 16 pivoted at 17 in the rear of the soiled towel roll and depending to a point near the bottom of the cabinet and having a cross panel 70 18 closing the space between the lower portion of the rails. Preferably, however, a hand hole 19 is provided in this panel through which the operator may reach, when placing a clean roll of toweling in the cabinet, and grasp the soiled end to pass it up over the edge of the panel in the shield and wind it upon the soiled towel roll. A shelf or flange 20 preferably forms a horizontal continuation of the lower end of the shield 75 and overhangs the brace 21 and is movable forward and back therein and co-operates with said brace to close the gap at the bottom of the cabinet in the rear of the clean towel roll and prevent any one from reaching 80 up into the cabinet at this point.

The side rails of the shield may be shorter so that their pivots will be lower down in the cabinet, nearer the level of the soiled towel roll. This, however, is a modification 85 in construction which I have thought so obvious as to be unnecessary of illustration.

A space 22 is provided between the shield and the rear wall of the cabinet wherein the soiled portion of the towel depends, and extends between the upper portions of the rails 16 forwardly to the soiled towel roll and there is wound upon this roll by the operation of the feed or control roll 11 beneath. The guideways, as indicated, have 90 preferably vertical extensions and the towel rolls are free to move vertically in these extensions, the clean towel roll dropping down as it decreases in size and the soiled towel roll raising in its guideways as the soiled 95 towel is wound thereon. Backward movement of the soiled towel is prevented by suitable means, preferably a latch 23, arranged to engage ratchet teeth on the hub of one of the sprocket wheels. This latch 100

allows freedom of revolution of the sprocket wheels in one direction and positively prevents backward movement thereof.

When this cabinet is set up, a loop of 5 clean towel will depend through the bottom of the cabinet and the user, grasping this, can unroll the desired amount, and as fast as the clean towel is unrolled, the soiled towel roll will be revolved to wind up the 10 used portion. This will continue until the clean towel is exhausted, when the cabinet is opened, the soiled towel removed, and a clean towel placed on the roll provided for that purpose.

15 The feed rolls 10 and 11 have roughened surfaces, preferably sand paper, to prevent the towel rolls from turning thereon, and, as shown in Figure 1, the guideway of the soiled towel roll and the location of the 20 guard or shield in the rear of the cabinet causes the soiled towel to be stretched at such an angle to its roll that when a backward pull is applied to the towel the soiled towel roll will be drawn against the walls 25 of the guideway and wedged between these walls and the roughened surface of the feed roll, and consequently backward movement of the soiled towel roll will be prevented. This is an important feature of the cabinet, as it positively prevents any malicious or uninstructed person from grasping the soiled portion of the towel and unwinding 30 the roll.

I claim as my invention:

35 1. A towel cabinet comprising a casing, clean and soiled towel rolls mounted therein, feed rolls contacting by gravity respectively with said towel rolls and having a driving connection between them, the clean 40 towel depending through the bottom of the cabinet and extending upwardly in the rear thereof to the soiled towel roll, a shield pivotally mounted vertically in the rear of said cabinet and a shelf on said shield projecting forwardly and preventing access to the 45 rear of the clean towel roll.

2. A towel cabinet comprising a casing, clean and soiled towel rolls mounted therein, feed rolls contacting by gravity respectively with said towel rolls and having a driving connection between them, the clean 50 towel depending below said cabinet and the soiled portion thereof being carried upwardly in the rear of said cabinet to the 55 soiled towel roll, a shield comprising side rails pivotally supported in the rear of said towel roll and depending in the rear of the cabinet and having a paneled lower portion in the rear of which the soiled towel 60 is stretched, and the upper portion of said shield having an edge over which the soiled towel 65 is carried forwardly to the soiled towel roll, said shield preventing contact of the soiled toweling with the clean towel 70 roll.

3. A towel cabinet comprising a casing, clean and soiled towel rolls mounted therein, feed rolls contacting respectively with said towel rolls and having a driving connection between them, the clean towel depending through the bottom of the cabinet and extending upwardly in the rear thereof to the soiled towel roll, a shield mounted in the rear of the cabinet and having an upper portion over which the soiled towel 75 passes to the soiled towel roll, a brace provided in said casing beneath said clean towel roll and said shield having a forwardly projecting shelf co-operating with said brace to close the bottom of said casing. 80

4. A towel cabinet comprising a casing, clean and soiled towel rolls mounted therein, feed rolls contacting respectively with said towel rolls and having a driving connection between them, the clean towel depending through the bottom of the cabinet and extending upwardly in the rear thereof to the soiled towel roll, a shield mounted in the rear of the cabinet and having an upper portion over which the soiled towel 85 passes to the soiled towel roll, a brace provided in said casing beneath said clean towel roll and said shield having a shelf arranged to overhang and co-operate with said brace to close the opening in the bottom of said casing. 90

5. A towel cabinet comprising a casing having slots therein, clean and soiled towel rolls mounted in the slots, feed rolls having roughened surfaces contacting respectively with said towel rolls, driving connections between said feed rolls, a shield pivoted in the rear of the casing whereby said shield may be pulled forward and the soiled towel conveniently passed back of it, 100 said shield having a towel guide so located as to guide the soiled towel to its roll at such an angle to the slots that backward pull applied to the soiled towel to unwind it from its roll will wedge the soiled towel 105 roll against the feed roll for the purpose specified. 110

6. A towel cabinet comprising a casing, clean and soiled towel rolls mounted therein, a feed roll contacting by gravity with one of said towel rolls, a second feed roll having a driving connection with the first feed roll, a clean towel depending from the cabinet, a shield pivoted in the rear of the cabinet and behind which the towel extends, said shield being movable towards the front of the cabinet to facilitate the insertion of the towel back of the shield and to prevent the soiled part of the towel from 115 contacting with the clean portion during the 120 normal operation of the device. 125

In witness whereof, I have hereunto set my hand this 10th day of December 1921.

GEORGE ADOLPH STEINER.
